UNITED STATES PATENT OFFICE.

GUENTHER BUECHNER AND HUGO SEMRAU, OF SCHENECTADY, NEW YORK.

PNEUMATO-ELECTRIC PIANO-PLAYER.

1,073,792.

Specification of Letters Patent.

Patented Sept. 23, 1913.

Application filed August 16, 1912. Serial No. 715,368.

To all whom it may concern:

Be it known that we, GUENTHER BUECHNER and HUGO SEMRAU, subjects of the Emperor of Germany, and residents of the city 5 of Schenectady, county of Schenectady, and State of New York, have invented certain new and useful Improvements in Pneumato-Electric Piano-Players, of which the following is a specification.

10 The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a bottom plan 20 view of a part of the air-chamber or box showing several of the contact-making-and-breaking units in position for use. Fig. 2 is a side view of the same as shown in Fig. 1. Fig. 3 is a cross-section taken on the line 25 3—3 in Fig. 1 through two of the circuit-making-and-breaking units provided with different forms of spark-arresters in accordance with our invention. Fig. 4 is a view similar to Fig. 3 showing the spark-arrester 30 as a preferred form of condenser. Fig. 5 is an inner end view of one of the circuit-making-and-breaking units detached. Fig. 6 is a diagrammatic view illustrating the use of a discharge-resistance as a spark-arrester. 35 Fig. 7 is a similar diagrammatic view illustrating the use of a condenser as a spark-arrester.

Certain features of the invention are applicable to different kinds of piano players, 40 but in its preferred form the invention is particularly adapted for piano players wherein the keys are operated by electro-magnets, the operation of which is controlled by a pneumatic contact-making-and-breaking apparatus adapted for use with a 45 perforated music-sheet.

Certain features of the invention are to facilitate the operation of the contacts in making and breaking the circuit; to simplify 50 the system of wiring; to facilitate repair of the contact-making-and-breaking devices; and to prevent sparking of the contact-breaking device.

Other objects of the invention will appear 55 in connection with the following description.

Referring to the drawings wherein the in-

vention is shown in preferred form, the air-chamber or box, 1, is constantly kept under a partial vacuum in any known manner, as by the use of bellows or the like not shown, 60 the air being extracted through the tube, 2. The auxiliary air-chambers, 3, are separated from the main air-chamber by the respective diaphragms, 4 and 4^a, the only connection between the main air-chamber and the auxiliary air-chambers being through the bleeds, 65 5. A series of ducts, 6, connect the respective auxiliary air-chambers, 3, with the openings in a tracker-board for a perforated music-sheet, which forms no part of our invention and which may be of any known form whereby the several auxiliary air-chambers, 3, are at certain times open to, and at certain other times closed to, the atmosphere. 70

As is well understood by those familiar with pneumatically operated piano players, whenever the auxiliary air-chamber, 3, is closed to the atmosphere, the pressure upon opposite sides of the diaphragm, 4 or 4^a, 80 will be equalized through the bleed, 5, and whenever an auxiliary air-chamber, 3, is open to the atmosphere, the atmospheric pressure upon the outer side of the diaphragm, 4 or 4^a, will exceed the main air-chamber pressure on the inner side of said diaphragm causing the diaphragm, which is flexible and adapted to yield, to bulge inwardly as shown at 4^a in Fig. 4. When not exposed to atmospheric pressure, the diaphragm extends straight across the back of the auxiliary air-chamber as shown at 4 in Fig. 4. 85 90

Our invention relates more particularly to means for utilizing this bulging or displacement of the diaphragm to close an electric-circuit containing an electro-magnet by energization of which a piano key is operated. 95

As the electro-magnetic means for operating the piano key forms no part of the present invention, we have omitted the same from the drawings. 100

In carrying out our invention, we provide the main air-chamber, 1, with a series of socket-apertures, 7, opposite the respective auxiliary air-chambers, 3, each of said sockets being adapted to receive a circuit-making-and-breaking unit and support the same in operative relationship to the respective diaphragm, 4. One of these circuit-making-and-breaking units is shown removed in Fig. 5. Each of these circuit- 110

making-and-breaking units comprises an insulating head or base, 8, upon which is fixed a metal sleeve, 9, and a centrally located binding post, 10, terminating at its inner end in a contact point, 11. The contact point, 11, is located in the path of a spring-contact, 12, mounted upon the inner end of the sleeve, 9, in position when the unit is inserted in one of the sockets, 7, to be engaged and operated by the oppositely located diaphragm, 4, when the latter is bulged or displaced inwardly as shown at 4^a in Fig. 4. As soon as the diaphragm is relieved from atmospheric pressure, it returns to the position shown at 4 in Fig. 4, whereupon the spring-contact, 12, automatically separates from the contact point, 11, to break the circuit. One side of the circuit is connected by a wire, 13, with the binding post, 10, and the other side of the circuit is connected through a bus-bar, 14, with the sleeve, 9, said bus-bar being located in the path of, and adapted to frictionally engage, said sleeve as the unit is inserted in the socket, 7.

To prevent sparking upon the breaking of the connection between the contacts, 11 and 12, we provide each of the circuit-making-and-breaking units with a contained spark-arrester. For certain purposes of the invention the contained spark-arrester may be of any known form adapted to comprise a part of the removable circuit-making-and-breaking unit. In Fig. 3 we have shown two forms of contained spark-arrester, one being a discharge resistance, 15, permanently connecting the sleeve, 9, with the binding post, 10. This discharge resistance, 15, is formed by a coil wound upon a spool, 16, fixed upon the head or base, 8, one end of the coil being connected with the sleeve and the other end with the binding post, 10.

To illustrate the operation of the discharge resistance, reference may be had to Fig. 6 wherein 11^a represents the contact point, 11, on the binding post; 12^a the spring contact, 12; 15^a the discharge resistance, 15; 18 the battery or generator; and 19 the electro-magnet. The discharge resistance, 15^a, forms a constant connection between the opposite sides of the switch, permitting the passage of sufficient current to relieve or arrest the sparking while not permitting the passage of sufficient current to energize the electro-magnet, 19. Any known form of discharge-resistance adapted to form a constituent part of the removable circuit-making-and-breaking unit may be employed. We have also shown a spark-arrester in the form of a condenser, 20, consisting of alternately arranged perforated disks of conductive and insulating material located within the sleeve, 21, encircling the post, 10, said conductive disks being connected in alternation with the sleeve 9,

and with the post, 10, through an inner sleeve, 21.

In Fig. 4 we have shown a spark-arrester in the form of a condenser, 22, the alternate conductive and insulating or dielectric, elements of which are spirally wound about the post, 10, within the sleeve, 9.

To illustrate the operation of the condenser as a spark-arrester, reference may be had to Fig. 7 wherein the parts are designated similarly to the parts in Fig. 6, except that a condenser, 20^a, is shown in place of the spark-coil, 15^a.

The circuit-making-and-breaking units above described are readily removed for examination and repair and are interchangeable with one another in their relationship to the sockets, 7, and to the diaphragms, 4.

What we claim as new and desire to secure by Letters Patent is—

1. In a piano-player, and in combination, an air-chamber having a pneumatically operated diaphragm; and a circuit-making-and-breaking unit removably mounted upon said air-chamber opposite said diaphragm, 90 said unit comprising a movable contact located in the path of said diaphragm in electrical connection with one side of an electric circuit, and a contact in the path of said movable contact in electrical connection 95 with the other side of said circuit.

2. In a piano-player, and in combination, an air-box provided with a plurality of air-chambers and with a like plurality of socket-openings opposite the respective air-chambers; pneumatically operated diaphragms for the respective air-chambers; and a like plurality of circuit-making-and-breaking units interchangeably insertible in the respective socket-openings, each of said units comprising a movable contact located in the path of said diaphragm in electrical connection with one side of an electric circuit, and a contact in the path of said movable contact in electrical connection with the other side of said 110 circuit.

3. In a piano-player, and in combination, an air-chamber having a pneumatically operated diaphragm; and a circuit-making-and-breaking unit removably mounted upon 115 said air-chamber opposite said diaphragm, said unit comprising a movable contact located in the path of said diaphragm in electrical connection with one side of an electric circuit, a contact in the path of said movable contact in electrical connection with the other side of said circuit, and a spark-arrester.

4. In a piano-player, and in combination, an air-chamber having a pneumatically 120 operated diaphragm; and a circuit-making-and-breaking unit removably supported upon said air-chamber opposite said diaphragm, said unit comprising a conductive sleeve in electrical connection with one side of an 130

electric circuit, a spring-contact mounted upon the inner end of said sleeve in the path of said diaphragm, and a contact in the path of said spring-contact in electrical connection with the other side of said circuit.

5. In a piano-player, and in combination, an air-chamber having a pneumatically operated diaphragm; and a circuit-making-and-breaking unit supported upon said air-chamber opposite said diaphragm, said unit having a contained spark-arrester.

10. In a piano-player, and in combination, an air chamber having a pneumatically operated diaphragm; and a circuit-making-and-breaking unit supported upon said air-chamber opposite said diaphragm, said unit having a contained condenser.

15. In a piano-player, and in combination, an air-chamber having a pneumatically operated diaphragm; and a circuit-making-and-breaking unit removably supported upon said air-chamber opposite said diaphragm, said unit comprising a conductive sleeve in electrical connection with one side 20 of an electric circuit, a movable contact mounted upon the inner end of said sleeve in the path of said diaphragm, an insulating

base, a binding post having a contact in the path of said movable contact, and a condenser contained within said sleeve surrounding said binding post in electrical connection with said sleeve and post.

25. In a piano-player, and in combination, an air-chamber having a pneumatically operated diaphragm and opposite thereto a socket; a circuit-making-and-breaking unit removably inserted in said socket, said unit comprising a conductive sleeve, a spring contact mounted upon the inner end of said sleeve in the path of said diaphragm, and a contact in the path of said spring contact in electrical connection with one side of an electric circuit; and a terminal-plate in electrical connection with the other side of said circuit permanently mounted upon said air-chamber in the path of said sleeve when said unit is inserted within the socket.

In testimony whereof, we have hereunto set our hands this 9th day of August, 1912.

GUENTHER BUECHNER.
HUGO SEMRAU.
